UNITED STATES PATENT OFFICE.

WARREN G. JONES AND FREDERICK H. HOGE, OF CHICAGO, ILLINOIS, ASSIGNEES TO
W. A. JONES FOUNDRY & MACHINE COMPANY, OF CHICAGO, ILLINOIS, A CORPOR-
ATION OF ILLINOIS.

SPEED REDUCER AND THE LIKE.

Application filed August 16, 1924. Serial No. 732,524.

This invention has to do with improvements in speed reducers and the like. More particularly it has to do with improvements in gear speed reducers in which the gearing 5 is so arranged that the power delivered by the driving shaft at one speed is transferred to the driven shaft and delivered thereby at a reduced speed.

More particularly the present invention 10 relates to an improved connection for delivering power from the driven shaft to the external mechanism. In many cases the power delivered by the driven shaft is to be taken off therefrom by a train of gearing. In 15 such case the gearing element on the driven shaft located outside of the speed reducer itself causes side thrusts to be exerted on the bearing of the driven shaft.

The main object of the present invention is 20 to provide an outboard bearing construction for giving additional support to the driven shaft and so as to better carry the aforesaid side thrusts and give the driven shaft the needed additional support. In this connection, the aforesaid outboard bearing also 25 serves to support the driven shaft at a position beyond the gear element thereon, so that it is supported at both sides of said gear element.

30 A further object of the invention is to provide a unit bearing element which can be readily attached to or removed from the end portion of the casing itself. This outboard bearing element is also so constructed that 35 it can be readily applied to gear speed reducers of standard constructions which are well known in the art and in very extended use at this time.

In connection with the above, a further object 40 is to provide an outboard bearing unit of such construction that it can be turned into different positions with respect to the axis of the casing of the gear speed reducer itself. This will make it possible to cause 45 the opening of the outboard bearing unit to face in any desired direction around a circle, so that the connection to the train of gears can be established from the speed reducer in any desired direction.

50 Other objects and uses of the invention will appear from a detailed description of the same, which consists in the features of

construction and combinations of parts hereinafter described and claimed.

In the drawings:

Figure 1 shows a vertical section through a typical speed reducer of well known form and construction having applied thereto an outboard bearing unit embodying the features of the present invention;

Fig. 2 shows a side elevation of the outboard bearing itself;

Fig. 3 shows an end elevation of an assembled speed reducer having applied thereto the outboard bearing unit;

Fig. 4 shows a view at right angles to that of Fig. 2; and

Fig. 5 shows a fragmentary view of the end of a gear speed reducer having one of the outboard bearing units applied thereto, 70 but rotated at 180° with respect to the position indicated in Figs. 1 and 3.

For purposes of convenience, the features of the present invention are herein shown as applied to a gear speed reducer of a specific 75 construction. This is done by way of illustration and not as a matter of limitation, except as we may limit ourselves in the claim.

Bearing the above in mind, the particular speed reducer unit indicated includes a cylindrical barrel-shaped casing 6 having its ends recessed, as shown at 7 and 8, to accommodate the end heads 9 and 10 respectively. The high speed shaft 11, usually the driving shaft, is journaled in the end head 9 at the 85 point 12 and carries the pinion 13 at its inner end. The low speed shaft 14 is journaled in the other end head 10 by the bearing 15 and carries at its inner end a gear 16. One or more back driving shafts 17 are 90 journaled in the end heads 9 and 10 by the bearings 18 and 19 respectively. Each of these back shafts 17 carries a gear 20 meshing with the pinion 13 and a pinion 21 meshing with the gear 16. As a consequence, the speed is reduced between the shafts 11 and 14. At the same time by placing a number of the back shafts 17 around the device, each one being properly geared to the pinion 13 and gear 16, the side thrusts 95 due to the speed reducer gears are eliminated and the driven shaft is driven without side thrusts.

At the low speed end of the device is

placed the outboard bearing unit 22. The same preferably includes a circular end flange 23 of proper size to seat around the flat peripheral portion 24 of the low speed end head 10, as clearly indicated in Fig. 1. The same tap screws 25 which are used for holding the end head 10 in place may also advantageously be used for securing the outboard bearing unit 22 in place, though this 10 is optional.

The outer portion of the unit 22 carries a bearing 26 which receives the end of the low speed shaft 14 and supports the same in a very firm manner. Preferably the outboard bearing unit is of generally cup shape, as shown in several of the figures, so that when turned into position where its open side faces upwardly it may be either wholly or partially filled with oil. It may also be reinforced with a number of radial ribs 27, if desired.

The gear 28 is mounted on the low speed shaft 14 intermediate between the bearings 15 and 26, so that the driven shaft is firmly 25 supported at both sides of said gear. Preferably the outboard bearing unit is open along one side, as indicated in Fig. 4 in particular, so as to expose the relatively large opening 29. Ordinarily, this opening 30 will be sufficiently deep and so shaped as to allow a portion of the gear 28 to project beyond the outboard bearing unit, as clearly indicated in Fig. 3. This will facilitate the application of the train of gears thereto.

In some cases it may be desired to allow for a free circulation of air through the outboard bearing unit. When this is the case an opening 30 may be formed in its lower portion, as shown in Fig. 1, but in many cases it will be found desirable to provide for the retention of oil within the lower portion of the device, in which case the presence

of the opening 30 should be dispensed with or said opening sealed.

Manifestly, the outboard bearing unit can 45 be turned into any desired direction when applied to the end of the speed reducer. For example, its open side may be made to face downwardly, as indicated in Fig. 5, or in any other direction.

While we have herein shown and described only a single embodiment of the features of our present invention, still we do not intend to limit ourselves to the same, except as we may do so in the claim.

We claim:

The combination with a circular end head of the casing of a gear speed reducer intended for permanent location and attachment to a structure, said casing having a 60 series of equally spaced securing bolts holding said end head in place, and the driven shaft projecting from said end head, of a segmental outboard bearing element in conjunction with said end head and intended 65 for attachment thereto at different positions of angular adjustment thereon, with the outboard bearing in line with the driven shaft aforesaid, said outboard bearing element having a circular outwardly projecting 70 flange at its attaching end adapted to seat against the peripheral portion at the end head of the casing aforesaid, said flange being perforated at equally spaced positions 75 corresponding to the spacing of the securing bolts aforesaid, said bearing of the outboard bearing element being adapted to receive the end portion of the driven shaft, and a gear element on the driven shaft intermediate between the end head and outboard bearing substantially as described.

WARREN G. JONES.
FREDERICK H. HOGE.
